UNITED STATES PATENT OFFICE.

JOHN F. WYNNE, OF ATLANTA, GEORGIA.

COMBINED COAL-SHOVEL AND ASH-SIEVE.

1,259,333.

Specification of Letters Patent. Patented Mar. 12, 1918.

Application filed July 16, 1917. Serial No. 180,876.

To all whom it may concern:

Be it known that I, JOHN F. WYNNE, a citizen of the United States, and a resident of Atlanta, in the county of Fulton and 5 State of Georgia, have invented a certain new and useful Improvement in Combined Coal-Shovels and Ash-Sieves, of which the following is a specification.

The present invention relates to a combined coal shovel and ash sieve, particularly for use with small coal stoves, although the same may be adapted for use with furnaces or the like.

An object of the present invention is to 15 provide a device of this character adapted to be used in the removal of coal from a firebox, grate or the like; a device which may be manipulated in the manner of an ordinary coal shovel; a device which comprises 20 but relatively few parts which may be quickly adjusted; and a device which may be easily and economically manufactured.

It is the further aim of the present invention to provide a combined coal shovel and 25 ash sieve which may be quickly adjusted by one hand for use as an ordinary coal shovel, and which may be adjusted by the hand supporting the device for use as a sieve for separating the fine particles of ashes from 30 the particles of coal, and which is provided with means for separating the fine particles of ashes so as the latter may be returned to the ash pit or to any other suitable place of deposit.

35 The above, and various other objects and advantages of this invention will be in part described, and in part understood, from the following detailed description of the present preferred embodiment, the same being 40 illustrated in the accompanying drawing wherein:

Figure 1 is a side elevation of a combined coal shovel and ash sieve constructed according to the present invention, the full lines 45 showing the device adjusted for use as a shovel, with the lower margin of the upper section dotted in, and the lower dotted lines showing the lower section of the device adjusted for use as an ash sieve.

50 Fig. 2 is a top plan view of the same.

Fig. 3 is a transverse section taken on a plane indicated substantially by the line 3—3 in Fig. 2.

Fig. 4 is a transverse section through the

handle portion of the device, disclosing the 55 yoke employed for connecting the sections.

Fig. 5 is a detail perspective view showing the strap employed for holding the yoke in position.

Referring to this drawing, the device comprises a pair of shovel sections 10 and 11 which are arranged in interfitting relation and which are provided in the usual manner with upstanding flanges at their marginal lateral edges. The shovel sections 10 and 11 merge at their inner ends into upwardly inclined handle portions 12 and 13 which are relatively narrow and are transversely curved to fit the hand for grasping the shovel sections and lifting the same. The 70 handles 12 and 13 are also interfitted and are provided at their upper ends with openings 14 therethrough adapted to receive a hinge 15. The hinge 15 may be in the form of a single length of wire which is rolled over to 75 provide a ring engaging through the openings 14 to hingedly connect the shovel sections. One end of the wire or hinge 15 is projected along the concaved upper face of the handle 12 and is bent downwardly to 80 form an arcuate finger 16 constituting a guide. The guide finger 16 engages through a pair of registering openings 17 formed in the handles 12 and 13 for holding the shovel sections in true alinement when the lower 85 section 11 is swung down into the position shown in dotted lines in Fig. 1.

The upper section 10 is provided in its bottom with a plurality of relatively large perforations 18 forming a sieve which is 90 closed by the imperforate bottom of the lower section 11 when the latter is swung up into the position shown in Fig. 1. When the sections are separated, as shown in dotted lines in Fig. 1, the upper section constitutes 95 a sieve and the lower section provides means for catching the fine particles which fall through the openings 18.

The sections 10 and 11 are further held in registry, and are limited in their movements 100 of separation, by a yoke which is in the form of a single length of wire bent to provide a pair of spaced-apart substantially parallel rods 19 and 20 which engage through perforations 21 formed in the handles 12 and 13, 105 and which are transversely spaced apart and arranged adjacent to the marginal edge portions of the handles. The openings 21

in the upper handle 12 may be in the form of notches formed in the lateral edge portions of the handle 12. The upper end of the rod 19, after passing through the opening 21, extends transversely across the upper handle 12 to the intermediate portion thereof and is then extended downwardly through openings 22 formed in the handle sections 12 and 13, and extends downwardly 5 in parallelism with the rods 19 and 20 to form a central guide and reinforcing rod 23. The rods 19 and 20 comprise the sides of the yoke and their integral lower ends are bent abruptly toward each other and are joined 10 in a depending loop 24 through which the lower end of the rod 23 is secured. The upper end of the rod 20, after passing through the openings 21 in the handles 12 and 13, extends transversely across the upper 15 side of the handle 12 to the intermediate portion thereof, and is looped about the upper end of the rod 23 and is then carried upwardly and rolled over to form a loop or ring 25 which extends transversely of the 20 handles 12 and 13 and is adapted to receive the finger or thumb therethrough. The yoke is held rigidly to the upper handle 12 by means of a strap 26, which latter is preferably formed from a strip of metal having 25 a perforation 27 intermediate its end through which the bottom of the loop 25 extends, and which is turned inwardly at its opposite extremities beneath the lateral edge portion of the handle 12. The inturned ends 30 of the strap 26 are provided with notches 28 adapted to receive the upper portions of the rods 19 and 20 therethrough. The notches 28 may be formed by stamping tongues 29 from the ends of the strap 26, 35 and bending the tongues 29 over against the outer exposed side of the strap. The tongues 29 are received in the outer ends of the notches 21 of the lower handle 13 when the handles are brought together. As the 40 tongues 29 fit in the notches 21 of the lower handle 13, the handles 12 and 13 may lie closely together so as to engage the lower shovel section 11 close against the lower side of the upper section 10. The bottom 45 of the yoke holds the lower handle 13 when it is swung down and prevents the separation of the handles beyond the desired limit.

In use, the hand may be grasped about the handle sections 12 and 13 to hold the 50 shovel sections 10 and 11 together, and the device may be used in the ordinary manner of a coal shovel. When it is desired to sift ashes or the like, it is only necessary to engage the hand or fingers with the loops 25 55 and allow the lower section 11 to swing down into the dotted position shown in Fig. 1. The yoke holds the lower section when it is swung down, and the guiding finger 16 assists the yoke in holding the sections of the device in true alinement.

When the device is to be used for sifting coal and ashes, taken from an open grate, the operator may rest the upper shovel section 10 upon one of the grate bars and by use of a poker stir the contents of the upper 70 section so that the ashes and fine particles will escape through the perforations 18. The ashes falling through the perforations are caught in the lower shovel section 11 from which they may slide by gravity into 75 the space beneath the grate. The yoke holds the lower shovel section 11 in an inclined position while the upper section 10 may be held in a horizontal plane so that the contents thereof will not tend to slide toward the open end of the shovel. 80

It is to be observed that the shovel may be made of but five different parts, three of which are susceptible of being made from stamped metal, while the other parts may be 85 made of wire. It is also understood that the device may be made in various sizes to suit conditions of use, such as for use with furnaces and the like.

It is of course understood that various 90 changes and modifications may be made in the details of construction and design of the above specifically described parts without departing from the spirit of this invention, such changes and modifications being restricted only by the scope of the following 95 claims.

I claim:

1. In a combined coal shovel and ash sieve, the combination of a pair of shovel 100 sections having handles extending therefrom, means for hingedly connecting the free ends of the handles together and in overlapping relation, and guiding means engaging the handles to hold the same in longitudinal register during the swinging of the same apart and the bringing of the handles together to separate and interfit the shovel sections.

2. In a combined coal shovel and ash 110 sieve, the combination of a pair of like shovel sections, handles on the sections, means for hingedly connecting the free ends of the handles together in superposed relation, the upper shovel section having a perforated bottom and the lower shovel section having an imperforate bottom, and a yoke 115 engaging the intermediate portions of the said handles in spaced relation from the hinged connection thereof and adapted to hold the handles and the shovel sections in vertical register and to limit the separation of the shovel sections.

3. In a combined coal shovel and ash 125 sieve, the combination of a pair of shovel sections having handle portions, a wire loop engaging through the free ends of the handle sections to hingedly connect the same and having one end arcuated and projecting downwardly through the handle sections 130

- to hold the same in vertical register, and a yoke secured to the upper handle section and projecting downwardly therefrom about the lower handle section to guide and limit the downward swinging of the same.
4. In a combined coal shovel and ash sieve, the combination of a pair of superposed shovel members, means for hingedly connecting the handles thereof, the upper shovel member having a perforated bottom, and the lower shovel member having an imperforate bottom, a yoke secured to the handle portion of the upper section and projecting downwardly through apertures in the lower handle section to guide the same, the lower handle section being adapted to engage in the lower end of the yoke to limit the downward swinging movement of the lower shovel section, and supporting means carried upon the upper end of the yoke for engagement with the hand to support the upper shovel section during the downwardly swinging movement of the lower shovel section.
5. In a combined coal shovel and ash sieve, the combination of a pair of superposed shovel sections, means for hingedly connecting the shovel sections together at one end, a yoke secured to the upper shovel section and provided with side rods projecting downwardly through the apertures in the lower shovel section to guide the same, the lower ends of said rods being turned inwardly toward each other to provide a support at the bottom of the yoke to limit the downward swinging movement of the lower shovel section, a finger loop carried upon the upper end of the yoke, and a securing strap engaging across the upper shovel section and having connection with the yoke to hold the latter to the upper shovel section.
6. In a combined coal shovel and ash sieve, the combination of a pair of superposed shovel sections, a loop connecting the free ends of the handles of the sections, a yoke carried by the upper handle and projecting downwardly through the lower handle to guide and limit the downward swinging movement of the same, a finger loop carried upon the upper end of the yoke adapted to be grasped for supporting the yoke, a connection between the yoke and the upper handle for securing the latter to the yoke for holding the upper handle section substantially horizontal during the downward swinging movement of the lower shovel section, said yoke being adapted to support the lower shovel section in an inclined position below the upper shovel section to receive material falling through the apertures of the upper shovel section.
7. In a combined coal shovel and ash sieve, the combination of a pair of superposed shovel sections, provided with handles, means for hingedly connecting the free ends of the handles, a yoke provided with side bars extending downwardly through the handle sections to guide the same and limit the separation thereof, a loop carried upon the upper end of the yoke adapted to receive the finger therethrough for supporting the yoke, and a strap engaging across the upper side of the upper handle and engaging the yoke to hold the latter to the upper handle, the ends of said strap being downturned about the lateral edge portions of the upper handle, and the lower handle having notches in its lateral edge portions adapted to receive the downturned ends of the strap when the handles are brought together.

JOHN F. WYNNE.
